(57) **CLAIM**

The ornamental design for a handbag cover with applied raindrop pattern, as shown and described.

DESCRIPTION

FIG. 1 is a front, environmental view of the handbag cover with applied raindrop pattern thereof;

FIG. 2 is a back view thereof;

FIG. 3 is a top view thereof;

FIG. 4 is a bottom view thereof;

FIG. 5 is a side view thereof;

FIG. 6 is an opposite side view thereof;

FIG. 7 is a perspective view thereof; and,

FIG. 8 is another perspective view thereof.

The broken lines showing a handbag cover are for the purposes of illustrating environment and form no part of the claimed design.
